UNITED STATES PATENT OFFICE.

CARL E. NORIN, OF JERSEY CITY, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed December 17, 1924. Serial No. 756,393.

This invention relates to knives for cutting off to length typed webs in typewriting machines, and one of its features relates to the provision of means whereby the cutting periphery of a revolvably mounted circular knife may be forced against the cutting edge of a straight knife and slid along for severing typed webs into predetermined lengths. 5
Another feature relates to the provision of means for holding the webs while the circular knife is moved along the straight knife while cutting said webs. 10
Still another feature relates to means for positively holding the cutting periphery of the circular knife against the sharp edge of the straight knife, for severing the webs, and at the same time providing a self-sharpening cutting device. 15
When a portion of the work-web has been typed upon, and through successive line-spacing, the leading edge of the work-web engages a paper-gage, it is then desired to cut it off, so that a fresh portion of the work-web may be typed on. The circular knife and the bail-piece which normally clear the work-web are forced downwardly, so that the bail will grip the work-web near the cutting edge of the straight knife. The circular knife is then forced downwardly against the work-web, and, through cam-like mechanism provided for the purpose, is simultaneously forced against the cutting edge of the straight knife. Then the circular knife is slid along a path parallel to the straight knife, and the work-web being interposed will therefore be severed between the sharp edge of the straight knife and the cutting periphery of the circular knife. 20
The bail-piece holding the work-web and the circular knife are then released, so that a new portion of the work-web may be fed forward. To this end there is provided a spring designed to hold the bail-piece in both its effective and ineffective positions. 25
Although this invention is illustrated as applied to an Underwood typewriting machine of the fan-fold type, it may nevertheless be used in connection with any kind of a typewriting machine. Furthermore, being a self-contained operating device, it may also be used as a card-cutter, or as an attach-

ment to any machine in which paper sheets or webs, or sheets of any kind of comparatively soft material, are to be severed or trimmed.

Other features and advantages will herein-after appear. 60

In the accompanying drawings,

Figure 1 is a front view, partly in cross-section, of the cutting device shown as an attachment to an Underwood typewriting machine. 65

Figure 2 is a cross-sectional view in elevation, showing the cutting device in its ineffective position mounted on the delivery table of an Underwood typewriting machine 70 of the fan-fold type.

Figure 3 is a perspective view of the circular knifeholder slidably mounted on a rock-shaft.

Figure 4 is a cross-sectional view in elevation, similar to Figure 2, but showing the cutting device in its effective position, as it would be when the circular knife is actually under pressure against the straight knife. 75

Figure 5 is a fragmentary detail view, 80 showing the retaining spring controlling the pressure bail.

In the Underwood fan-fold typewriting machine, a platen 10 is journaled in a swing-frame which includes end plates 11 and 12, journaled in a front shaft 13, extending across the carriage, so that the platen may be swung forwardly in line with the work-sheet on the fan-fold table and clear of the feed-rolls 14 and 15, which usually co-operate with the platen for feeding the work-sheet in line-space direction. The platen is shown geared to the line-space mechanism by means of pinions 16 fast on its axle 17, 85 said pinions meshing with idlers 18 fast on the front shaft 13, which idlers, in turn, mesh with pinions 19 fast on the shafts 20 which carry finger-wheels 21 for operating the platen, and are journaled in platen-frames 22. 90
100

According to the method of handling the work in this invention, a web 23 is drawn from the rear of the machine over a rear table 24, down around the platen, past the feed-rolls to the printing line, opposite types 25 on type-bars 26, and then up and rearwardly over a front table 27, upon which the cutting attachment which forms the subject of this invention is mounted. In the usual operation of these machines, the web 110

is line-spaced after each line of typing until the leading edge thereof strikes a gage 28, which is slidably mounted on a supporting member 29 fast to the front table 27.

Having now written upon the web, and the web having been fed by successive line-spacing up to the gage 28, it is desired to cut it off so that a new section of the web may be typed upon, and so on. To this end, a bail 30, which extends parallel to the platen and is pivotally mounted on a cross-shaft 31, is swung downwardly from a position shown in Figure 2 to that shown in Figure 4, so that the web will be gripped between said bail 15 and a straight knife 32 which forms an integral part of said front table 27. Springs 33, at each end of the bail 30 normally hold the same in its ineffective position by engaging with a notch 34 cut at the rear of the 20 side arms of said bail beyond its rocking shaft, so that, when the bail is swung downwardly, and the springs are thrown out of engagement with the notches 34, the point 35 formed on the springs 33 is then bearing 25 on the bail at a point beyond its fulcrum, and therefore holds the bail 30 down against the knife 32, thereby gripping the web 23 near the cutting edge 36 of the knife 32. The exact position of a circular cutter 37 relatively to the web, previous to its being cut 30 after the bail has been thrown in its effective position, is not shown in the drawings, as the edge of the cutter 37 will lie on the web 23, and its relative position to a cross-bar 38 will be as shown in Figure 2. The function of said bar 38 is to force the cutter 37 against the cutting edge 36 of the knife 32, and to this end it is fastened to the bail 30, of which it forms an integral part. The 40 circular cutter 37 is revolvably mounted on a screw 39 fast to a housing 40, which is in turn rockably and slidably mounted on the cross-shaft 31 upon which the bail 30 is swung, so that, by gripping the housing 40, 45 and by forcing the same downwardly at the same time, it may be slid along the shaft 31, as the web is severed between the cutting edge of the knife 32 and the cutting edge 41 of the cutter 37.

In order that the circular cutter may be positively held against the cutting edge of the knife while the web is being severed, there is provided mechanism which comprises a conical backing 42 operatively engaging with the cross-shaft 31, and a spring 43 housed in the hub of the cutter 37. The head of the screw 39 takes the thrust of the spring 43, which forces the cutter away from the head of the screw, and holds it 50 against the housing 40, so that, when the housing is rocked on the cross-shaft 31, and the circular knife is forced forwardly by the conical backing 42 and the bar 38, the cutting edge 41 of the cutter 37 is held against 55 the cutting edge 36 of the knife 32. It will

be noted that the housing, as it is shown in the drawings, is formed out of a single piece of flat sheet-metal, and comprises a hood 44 for protecting the fingers of the operative, the outside of the hood being knurled to facilitate its being gripped and slid along the bar 38, upon which it is mounted, by means of ears 45, which are formed outwardly from a downwardly-extending connecting piece 46, in which there is a tapped hole 47 for receiving the screw 39.

The knife 32 is fastened to a bracket 48 by means of screws 49, and said bracket is, in turn, fastened to the table 27 by means of the rivets 50. A downwardly and forwardly extending bend 51, which forms an integral part of the table 27, is provided under the knife 32 for stiffening the same. Said bracket 48 is provided with upwardly-extending ears 52 for supporting the shaft 31, 85 upon which the circular knife and the bail are mounted.

In order that the bail 30 may be thrown to its ineffective position, so that a fresh portion of the web may be fed forward and typed upon, there is provided a handle 53 which forms an integral part of the bail 30. Said handle is forced rearwardly, and the bail is swung to a position, as shown in Figure 2, in which position it is held by means 90 of the springs 33 which engage the notches 34 in said bail. It will be noted that the Underwood machine is provided with a web-guiding plate 54 which holds the leading edge of the web after being cut off, and 100 guides it under the bail and the knife as it is fed forward.

Variations may be resorted to within the scope of the invention, and portions of the improvements may be used without others. 105

Having thus described my invention, I claim:

1. In a typewriting machine having a platen, a sheet-cutting device including a straight knife-blade, a displaceably-mounted revoluble knife normally disposed above said straight blade, so that a work-sheet may be passed therebetween, a handle for moving said revoluble knife first downwardly and then along said straight knife-blade in 110 shearing engagement therewith for severing a work-web on the platen, and means actuated upon downward action of said handle for urging said revoluble knife squarely against said straight blade, and mechanically maintaining such engagement of the revoluble knife as it moves along the straight blade, whereby said revoluble knife and said blade will be kept in close shearing engagement with each other regardless 115 of the wear on them occasioned by their use.

2. In a paper-cutter, the combination of a table, a knife having a straight cutting edge, a revolvably mounted circular knife having a cutting periphery co-operating with said 120

- straight edge, a guideway for controlling the movement of the circular knife along a path parallel to said straight cutting edge, manual means for positively forcing the circular knife against the straight cutting edge during the operation thereof, and means for holding a work-sheet along the straight cutting edge, said last-mentioned means including a bail-piece pivotally mounted at the ends thereof, and resilient means for holding said bail-piece in either effective or ineffective position.
3. In a work-sheet severing device for typewriting machines, the combination of a table having a straight cutting edge, a revolvably mounted circular knife, a bar parallel to said straight cutting edge for guiding the rectilinear travel of said circular knife, and manual means co-operating with said bar for positively forcing the circular knife against the straight cutting edge, said means including a tapered hub fast to the circular knife and means for operatively connecting said hub with the bar in a manner to move the circular knife toward the cutting edge when the latter is operated.
4. In a paper-cutter, the combination of a table having a straight cutting edge, a revolvably mounted circular knife operatively mounted adjacent said table and overlying the same, a bar parallel to said straight cutting edge for guiding the rectilinear travel of said circular knife, means whereby the circular knife may be forced against the straight cutting edge and slid along a line parallel thereto, said means including a finger-piece upon which the circular knife is revolvably mounted, bearings forming an integral part of said finger-piece slidably mounted on said bar, and a pressure bar across said table co-operating with a conical hub which forms an integral part of said circular knife.
5. In a paper-cutter, the combination of a table, a straight knife forming a part of said table, a revolvably-mounted circular knife disposed above said table for passing a work-sheet under said circular knife, means whereby the circular knife may be moved downwardly and be slid along said straight knife in shearing engagement therewith, and spring-pressed means for clamping a sheet to be severed along a line parallel to said straight knife against said table.
6. In a paper-cutter, the combination of a table, a straight knife forming an integral part of said table, a revolvably mounted circular knife adjacent said table and means whereby the circular knife may be slid in a line parallel to said straight knife, and means for clamping a sheet to be severed along a line parallel to said straight knife against said table, said last-mentioned means including a bail-piece rockably mounted on a shaft parallel to and overlying said table and a spring operatively connected to actuate said bail-piece for effectively rendering the same effective or ineffective.
7. In a paper-cutter, the combination of a table, a straight knife forming an integral part of said table, a revolvably mounted circular knife adjacent said table and means whereby the circular knife may be slid in a line parallel to said straight knife, means for clamping a sheet to be severed along a line parallel to said straight knife against said table, said last-mentioned means including a bail-piece rockably mounted on a shaft parallel to and overlying said table and a spring operatively connected to actuate said bail-piece for effectively rendering the same effective or ineffective, and means whereby the circular knife may be forced against the straight knife while cutting through the sheet on the table.
8. A sheet-cutting device comprising a table, a straight knife having a sharp edge fast upon said table, a shaft parallel to the table and overlying the same, a bail-piece rockably mounted upon said shaft for effectively holding a sheet of comparatively soft material in its cutting position, so that the line through which it is desired to sever the same will lie adjacent the sharp edge of said straight knife, a spring operatively connected to said bail-piece for rendering the same effective or ineffective, a housing rockably and slidably mounted on said shaft for carrying the circular knife revolvably mounted thereon, and means for effectively holding the circular knife against the sharp edge of the straight knife.
9. A sheet-cutting device comprising a table, a straight knife having a sharp edge fast upon said table, a shaft parallel to the table and overlying the same, a bail-piece rockably mounted upon said shaft for effectively holding a sheet of comparatively soft material in its cutting position, so that the line through which it is desired to sever the same will lie adjacent the sharp edge of said straight knife, a spring operatively connected to said bail-piece for rendering the same effective or ineffective, a housing rockably and slidably mounted on said shaft for carrying the circular knife revolvably mounted thereon, and means for effectively holding the circular knife against the sharp edge of the straight knife, said means comprising a second shaft fast to the ends of the bail-piece co-operating with a tapered portion of the hub which forms an integral part of the circular knife and a spring in the hub wound around a pivot which supports the circular knife for effectively forcing the circular knife away from the cutting edge.
10. In a typewriting machine, the combination with a revoluble platen, of a table at the delivery side of said platen, a straight knife parallel to said platen and overlying

- the same, a circular knife co-operating with said straight knife for severing work-sheets disposed to be passed around said platen, means for controlling the travel of said circular knife, including a cross-bar overlying said table and parallel to the platen and a housing disposed to be slid along said cross-bar and upon which the circular knife is revolutely mounted, and means whereby 5 the circular knife may be held against the straight knife as the housing carrying the circular knife is slid along said cross-bar, said last-mentioned means including a tapered hub forming an integral part of said circular knife, a second cross-bar co-operating with the tapered hub of the circular knife and a spring for effectively forcing the circular knife away from the straight knife. 10
11. In a typewriting machine, the combination with a revolute platen, of a table at the delivery side of said platen, a straight knife forming an integral part of said table, a circular knife disposed to be moved in shearing relation with the straight knife for 15 severing work-sheets, and means for gripping the work-sheets along a line parallel to said straight knife, said means including a bail-piece pivotally mounted at the ends thereof, and resilient means for holding the bail-piece in either effective or ineffective position. 20
12. In a typewriting machine, the combination with a revolute platen, of a table at the delivery side of said platen, a straight knife forming an integral part of said table, a circular knife disposed to be moved along 25
- the straight knife for cutting off work-sheets, and means for gripping the work-sheets along a line parallel to said straight knife, said means comprising a bail-piece 40 rockably mounted on a cross-shaft which forms an integral part of said table and a spring for effectively holding said bail-piece either in its effective or ineffective position. 45
13. In a typewriting machine, the combination with a revolute platen, of a sheet-cutting device comprising a table, a straight knife having a sharp edge fast upon said table, a shaft parallel to the table and overlying the same, a bail-piece rockably mounted upon said shaft for effectively holding a sheet of comparatively soft material in its cutting position, so that the line through which it is desired to sever the same will lie adjacent the sharp edge of said straight 50 knife, a spring operatively connected to said bail-piece for rendering the same effective or ineffective, a housing rockably and slidably mounted on said shaft for carrying the circular knife revolutely mounted thereon, and means for effectively holding the circular knife against the sharp edge of the straight knife, said means comprising a second shaft fast to the ends of the bail-piece co-operating with a tapered portion of the hub which forms an integral part of the circular knife and a spring in the hub wound around a pivot which supports the circular knife for effectively forcing the circular knife away 55 from the cutting edge. 60
- 65

CARL E. NORIN.
